ELECTRIC SWITCH CONSTRUCTION

Filed June 5, 1939

UNITED STATES PATENT OFFICE

2,233,336

ELECTRIC SWITCH CONSTRUCTION

Robert H. Bentley, Hartford, Conn., assignor to
 The Arrow-Hart & Hegeman Electric Company,
 Hartford, Conn., a corporation of Connecticut

Application June 5, 1939, Serial No. 277,512

4 Claims. (Cl. 200—168)

This invention relates to electric switches. More particularly it relates to electric switches in which one or more bridging contacts are employed and are insulated from the actuating mechanism of the switch.

It is an object of my invention to provide an improved mounting for bridging contacts in an electric switch, wherein the bridging contacts may adjust themselves to irregularities in position and form of fixed contacts. Another object of my invention is to provide a mounting for bridging contacts in an electric switch, which mounting will permit the use of one or several contacts, as may be required. Another object of my invention is to provide an improved mounting for bridging contacts of an electric switch in which the contacts are mounted upon the insulating hub and are insulated from the switch actuating mechanism. Other objects and advantages of my invention will appear as it is described in connection with the accompanying drawing.

In the drawing—

Fig. 1 is an end elevation view of switch actuating mechanism and a contact-carrying hub construction embodying my invention;

Fig. 2 is an exploded perspective view of the hub and contact and a portion of the bearing-support for the hub;

Fig. 3 is a side elevation view of the switch actuating mechanism with the hub and switch contact removed therefrom;

Fig. 4 is an end elevation view partly in section, showing my improved contact mounting in assembled relation in a switch;

Fig. 5 is an end view of the hub which carries the bridging contacts.

Referring to the drawing, it will be noted that the switch mechanism is mounted within an insulating casing 10 having a hollow main body portion 12 open at the bottom and a portion 14 to cover the bottom. The switch may be actuated manually by a handle 16 extending through the top of the body 12. The handle may be rocked to cause a switch yoke 18 to rock within V-shaped openings 20 in each of the side plates 22 and 24 of a switch frame. These side plates may be secured together by end plates 26 and the whole frame may be attached to the base 14 by bolts 28. The yoke 18 may be caused to move with a snap motion by reason of the employment of a tension spring 30 which may be actuated by the handle 16 in any suitable fashion. Inasmuch as the details of the operating mechanism of the switch form no part of this

invention and may be varied according to the teachings in the prior art, a more detailed description of this actuating mechanism is unnecessary.

The switch yoke 18 is of U-shape and has 5 lateral extensions 32 from each of its parallel arms. The upper ends of the parallel arms of the yoke 18 rest against the apex of the V-opening 20 in the frame members conventionally and afford bearing means for the yoke 18 to rock 10 within the opening 20. The extensions 32 are of irregular contour, being stepped to provide large portions 32a and reduced portions 32b which extend further than the portions 32a

On the extensions 32 are mounted hubs 34 15 of insulating material. These hubs are generally cylindrical in shape, having an enlarged cylindrical end 36 and a collar portion 38 between the enlarged end 36 and the main body portion of the hub. At the opposite end 40 of the hub 20 the end is reduced, while extending longitudinally between this reduced end and the collar 38 are three channels or flutes 42 spaced 120° apart around the hub in position to receive keys 44 of identical bridging contact assemblies 45 and 47. 25

Referring to the bridging contact member 45, for example, the contact may be made of two similar complementary stamped resilient sheet metal members 48 having contact portions 50 on the ends of radially extending arms which 30 proceed from a circular central portion which is apertured so that the contact assembly may slide onto the shank of the hub. The two members 48, just described, may be secured together by a metal ring 52 having several fingers 54 extending 35 therefrom and bent around the two members of the contact. Thus, when the two stamped sheet metal members 48 are placed face to face and the securing ring 52 is placed against one of the outside faces of these two members and the fingers 54 are bent around the contact members, a permanent contact assembly is formed. Each of the contact members 48 and the securing ring 52 as well, will have keys 44 extending radially 40 inward and in register with one another. Preferably the ends 50 of the contacts will be flared so as to embrace a stationary contact member (51 or 53) as the movable contact comes into engagement with the stationary contact. One or more contact assemblies may be slid upon the 45 hub 34 as occasion requires so that a single pole or a multi-pole switch may be created.

In the enlarged end 36 of the hub there is provided a slot 55 having configuration similar to the extensions 32 of the switch yoke 18 so 55

that the hub may fit upon the extensions and turn therewith as the yoke is rocked.

In assembling the yoke and contact assemblies in the switch cover 12 with the operating mechanism of the switch, the contact assemblies may be slid upon the hubs and then the hubs fitted to the extensions 32 and then the switch as thus far assembled may be slid into the casing body 12.

10 In order that the hub may not slide endwise off of the extensions 32, the reduced end 40 of the hub abuts the bottom of a channel 66 in the side wall of the casing body 12. When the hub is in its proper position a bearing member or insert 62 of insulating material is fitted into the channel 66 between the hub and the bottom 14 of the switch casing. The upper end of the insert is arcuate (see Fig. 2) to form a bearing surface for the reduced end 40 of the hub; and the lower end of the insert rests upon the bottom 14 20 of the casing when the switch is fully assembled. Preferably the casing will be made of molded insulating material and will be provided with an arcuate surface 66 adjacent the enlarged head 36 of the hub, forming a bearing therefor.

25 In order that flame or gases of an arc incident to contact separation may not interplay between the contacts or between any contact and the frame plates 22 and 24, baffle plates 68 and 70 of fibrous insulating material may be provided to 30 partition off the interior of the switch so that each movable contact will operate in its own compartment.

From the foregoing it may now be seen that when the hub is assembled upon the extension 32 35 and is in position in the casing, it is supported by the extension 32 at one end and turns in the bearing surface 66 adjacent that end while at the other end the bearing insert member 62 and the casing itself will provide a support and bearing 40 for the reduced end 40. Endwise movement of the hub is prevented by its abutment with the side wall of the cover 12.

Due to the fact that the contact assemblies are 45 slideable axially along the hub, they may accommodate themselves to irregularities of the fixed contacts with which they cooperate so that the fixed contacts may be made of stamped metal parts and need not be accurately fabricated or machined.

50 From the foregoing, it will be obvious that I have provided a simple and effective means of mounting bridging switch contacts in a single pole or multi-pole switch and that the invention provides for the use of one or several poles 55 without the necessity of material altering the switch construction. Also, I have provided a mounting which permits automatic or self-ad-

justment of the bridging contacts to the fixed contacts.

Many modifications within the scope of my invention will occur to those skilled in the art. Therefore I do not limit the invention to the 5 specific embodiment shown and described.

I claim—

1. In an electric switch, a casing, a rockable switching member having a lateral extension, an insulating hub having on one end a slot to receive said extension and on the other end a bearing surface, a contact assembly axially slideable on said hub and adapted to accommodate itself to irregularities in fixed contacts, said casing having a channel to enable said hub to be slid into assembled position, and an insulating member fitting in said channel and having a bearing surface cooperating with bearing surface of the hub.

2. In an electric switch, a casing, a rockable switching member having a lateral extension, an insulating hub having on one end a slot to receive said extension and on the other end a bearing surface, a contact assembly axially slideable on said hub, said hub being fluted and said contact assembly having a key fitting in said fluted 25 to cause turning of said contact assembly with said hub, said contact assembly being loosely mounted on said hub to accommodate itself to irregularities in fixed contacts, said casing having a channel to enable said hub to be slid into assembled position, and an insulating member fitting in said channel and having a bearing surface cooperating with bearing surface of the hub.

3. In an electric switch, a casing, a rockable switching member having a lateral extension, a 35 unitary insulating hub having on one end a slot to receive said extension and on the other end a bearing surface, said other end abutting said casing whereby said hub is held against endwise movement, a contact member axially slideable on 40 said hub and adapted to accommodate itself to irregularities in fixed contacts, and bearing means in said casing for said bearing surface.

4. In an electric switch, a casing, a rockable switching member having a lateral extension, an 45 insulating hub having on one end a slot to receive said extension and on the other end a bearing surface, said other end abutting said casing whereby said hub is held against endwise movement, a contact assembly axially slideable on 50 said hub and adapted to accommodate itself to irregularities in fixed contacts, a channel in said casing receiving said other end of said hub, and an insert of insulating material in said channel and having a bearing surface for said bearing 55 surface of the hub.

ROBERT H. BENTLEY.
